CLAIM

We claim the ornamental design for a power pack with light tube, as shown and described.

DESCRIPTION

FIG. 1 is a perspective view of the power pack with light tube, showing our new design;

FIG. 2 is a side elevation view thereof;

FIG. 3 is a side elevation view thereof from the opposite side of FIG. 2;

FIG. 4 is a front view thereof;

FIG. 5 is a rear view thereof;

FIG. 6 is a top view thereof; and,

FIG. 7 is a bottom view thereof.

The broken lines illustrate portions of the power pack with light tube that form no part of the claimed design.

1 Claim, 2 Drawing Sheets(56)
